UNITED STATES PATENT OFFICE.

WILLIAM J. ROHR, OF MASSAPEQUA, NEW YORK.

GREASE-CUP.

1,320,414.

Specification of Letters Patent. Patented Nov. 4, 1919.

Application filed February 8, 1919. Serial No. 275,864.

To all whom it may concern:

Be it known that I, WILLIAM J. ROHR, a citizen of the United States, residing at Massapequa, in the county of Nassau and State of New York, have made certain new and useful Improvements in Grease-Cups; and I hereby declare the following to be a description thereof, reference being had to the accompanying drawings, making part 10 of this specification.

The invention relates to devices for supplying grease or lubricating material to engine bearings and is designed to facilitate the operation of supplying the lubricant 15 and also provide for the stability of the parts.

In the drawings:—

Figure 1, is an elevation or side view of my device.

20 Fig. 2, is a vertical cross-section of Fig. 1 with the cover unlocked.

Fig. 3, is a detached view of the cover and top of cup.

Fig. 4, is a top view of Figs. 1 and 2 with 25 the detachable cover plate removed.

Fig. 5, is a separate view of the cover plate.

Fig. 6, is a separate view of the securing plate and

30 Fig. 7, is a separate view of the cover handle piece.

In the use of grease cups, it is important that the grease receptacle should always be available for use. In many cases the upper 35 portion or deep cap holding the grease is readily unscrewed or detached from the stock or base which is the part fixed to the bearings. The grease container is usually connected with the stock by being screwed

40 or slipped onto it after the cup is filled with the grease, and the grease is then fed to the bearing by screwing the upper half farther on the body portion of the cup. In devices of this construction the grease holding

45 cap is often misplaced or lost, when once removed from its stock and is also difficult to fit in place, after being filled with grease, as the screw threads fail to readily take hold.

Another important point is that the grease 50 holding cup is often loosened and lost by jarring of the machine.

The improved device embodies the use of a grease receiver and holder which is not removed from the stock or body of the cup.

55 In the drawings A, represents the stock or base of the device which is hollow and pro-

vided at its narrow end with an exterior threaded terminal a, designed to be screwed into the bearing; the bearing not being shown. For this purpose the middle portion is made hexagon on its exterior at a¹. 60

The upper part of the stock or base A, is broadened out and terminates at its top in a projecting rim b, having an exterior threaded surface. The lower end has an outlet c, to convey the lubricant to the bearing. 65

Secured to the base A, is the grease container B, which is threaded on its interior surface to match the threaded rim b. In constructing my device when the grease container B, is fitted onto the base A, its lower portion is screwed past the rim b. The lower thread b¹ is then turned in or mutilated so it cannot be removed by unscrewing but is permanently locked to the base 70 A. Even where the entire device is removed from the bearing the cap and stock will not be separated in general use. 75

The top of the grease container B, has an inwardly projecting rim C, with an irregular shaped opening as shown in Fig. 4, comprising a circular center g, and bays g¹ g² on opposite sides of its circumference. Adapted to fit in this opening is a cover plate d, the outer part of which extends over the rim 80 C and has a depressed or countersunk central portion of the same contour as the opening g, g¹, in the rim C, and a circular central opening g¹¹, less than the area of the circular part of the depression in the plate d. 85

Adapted to lie in the central part of the depression g, of the cover d, is a circular plate h, and on the under side of the cover d, is a catch plate i; the plan of which is shown separately in Fig. 6. This catch 90 plate i, is greater in circumference in its central part than the opening g¹¹, and has wings k, k and is punctured at its central portion within the radius of the opening g¹¹ forming holes l, l which register with corresponding openings in the circular plate h. 100

A handle or thumb piece m, for the cover plate is shown separately in Fig. 7. It has two projections o, o, on its lower part which are positioned to pass through the openings h, h, in circular plate h, and the openings l, l in the catch plate i. The prongs o, o, and the openings l, l, and h¹, h¹, in the plate h, and i being within the radius of the central opening g¹¹, of the cover plate d. The 110 elements d, h, i, and m are secured together by passing the projections o, o, through

them and riveting the ends of o , o . This leaves the circular plate h , and the catch plate i , free to turn while the cover plate d , remains stationary and resting on the rim C.

- On the under side of the rim C, is a slight projection p , forming a stop against which the extended end of the catch plate i , will contact, thereby forming a means for 10 the fingers to turn the grease container B by the handle m , when desired and which will screw it down to feed the grease to the bearing. The handle m , is also used to unscrew the receiver B when empty, to its 15 limit, but by reason of my novel construction of cover when thus unscrewing, the catch plate i , will be turned and released and the entire cover plate d entirely loosened before sufficient pressure is exerted to 20 jam the broken or mutilated thread at the bottom of B on the threads of the base A. At one side of the grease container B, near the outer circumference the rim and the cover plate are pierced with holes s , s , and 25 a ring r , is inserted which passes through both and ties them together. This insures their proper replacement even in the dark after the grease cup has been filled.

By the foregoing description it will be 30 seen that the interior of the grease receiver is readily accessible for filling and the contents may be easily forced to the bearing by manipulating the handle m . The grease container is inseparable from its base and 35 the cover is attached to it so that neither are subject to loss, or the disadvantage of fitting together.

In referring to the lower thread of the grease container as being mutilated, it is

meant that the revolution of the tap shall 40 be stopped when it reaches the limit, but as this might result in jamming the cover, construction is designed to overcome such result.

What I claim as my invention and desire 45 to secure by Letters Patent is:

1. In a grease cup of the class shown, a grease confining and discharging device comprising a grease container cylindrical in form with threaded interior wall open 50 at one end and an inwardly projecting rim at the other end, an adjustable cover fitted in said inwardly projecting rim, lubricant confining means for securing said cover to the rim by circular movement and a base 55 threaded to receive the container and permanently fastened thereto, substantially as shown and described.

2. In a grease cup of the class shown a grease container having in combination a 60 cylindrical body with an inwardly projecting rim C and a lubricant confining cover composed of the catch plate element i , sliding plate h , cover plate d , and a handle element m , substantially as and for the purposes shown and described.

3. In a grease cup of the class shown, the threaded base plug A, the threaded grease container B, with mutilated lower thread and having an inwardly projecting 70 rim C, in combination with a lubricant confining cover composed of the catch plate element i , sliding plate h , cover plate d , and a handle element m , together with a stop projection p , located on the rim C, so as to 75 arrest the revolution of the catch plate i , substantially as shown and described.

WM. J. ROHR.
